UNITED STATES PATENT OFFICE.

SHUGO TANAKA, OF CHICAGO, ILLINOIS.

DESIGN FOR A PILLOW-COVER.

46,329.

Specification for Design. Patented Aug. 25, 1914.

Application filed June 19, 1914. Serial No. 846,211. Term of patent 7 years.

To all whom it may concern:

Be it known that I, SHUGO TANAKA, a subject of the Emperor of Japan, residing at Chicago, in the county of Cook and State of Illinois, have invented a new, original, and ornamental Design for Pillow-Covers, of which the following is a specification, reference being had to the accompanying drawing, in which a plan view of the design is shown.

I claim:

The ornamental design for a pillow cover, as shown.

In testimony whereof I affix my signature, in the presence of two witnesses.

SHUGO TANAKA.

Witnesses:
